UNITED STATES PATENT OFFICE.

THOMAS O. SCHRADER, OF ALLENTOWN, PENNSYLVANIA, ASSIGNOR TO DENT HARDWARE CO., OF FULLERTON, PENNSYLVANIA, A CORPORATION OF PENNSYLVANIA.

LATCH DEVICE FOR REFRIGERATOR DOORS.

Application filed July 14, 1925. Serial No. 43,474.

This invention, generally stated, relates to latching attachments and has more especial relation to automatic latching devices for refrigerators and the like.

5 The leading object of the present invention is to provide a device of the character above stated which is of simple, efficient and inexpensive construction; which may be readily applied to refrigerator doors; and 10 which is particularly efficient and effective for refrigerators of massive size such as are used by meat packers and the like.

Other and further objects of the present invention reside in the provision of novel 15 construction and arrangement of parts for attaining the results sought by the leading object. Other and further objects not at this time appearing will be hereinafter more fully described.

20 The invention consists of the novel construction hereinafter described and finally claimed.

The nature, characteristic features and scope of the invention will be more fully understood from the following description taken in connection with the accompanying drawings forming part hereof, and in which:

25 Fig. 1, is a fragmentary view in front elevation of a refrigerator casing and door equipped with a latching attachment embodying the invention, the door shown being in closed and latched position.

30 Fig. 2, is a view of the latching attachment, locking from the rear, and detached from the refrigerator door.

Fig. 3, is a view in end elevation of Fig. 2.

Fig. 4, is a rear view of the part shown in Fig. 2 with the operating parts removed.

35 Fig. 5, is a view in cross section taken upon the line 5—5 of Fig. 4.

Fig. 6, is a view similar to Fig. 2 with the closure plate removed, illustrating operative parts.

40 Fig. 7, is a view of the swinging bolt.

45 Fig. 8, is a fragmentary view in elevation of the operating handle; and

Fig. 9, is a view in side elevation of the keeper shown in Fig. 1.

50 For the purpose of illustrating my invention I have shown in the accompanying drawings one form thereof which is at present preferred by me, since the same has been found in practice to give satisfactory and reliable results, although it is to be understood 55 that the various instrumentalities of which

my invention consists can be variously arranged and organized and that my invention is not limited to the precise arrangement and organization of the instrumentalities as herein shown and described.

60 The reference numeral 1 designates a refrigerator casing and 2 a refrigerator door. Secured to the refrigerator door by means of screws 3 is a casing 4 preferably cast in integral form and provided upon the front face thereof with lugs 5 the front wall of casing 4 being slotted as at 6 between said lugs 5. Pivoted between the lugs 5 upon a pivoted bar 7 is a vertically arranged handle 8, the upper and inner end of which is provided with a rearwardly extending projection 9 which has a loose fit within opening 10 of a swinging bolt 11. The swinging bolt 11 has a loose fit with a stud 12 formed integral with casing 4, the 65 swinging bolt 11 being apertured as at 13 for said loose fit with respect to stud 12. Concentric with stud 12 is a raised portion 13 and extended from said raised portion 13 is another raised portion 14. The inner face 70 of the swinging bolt 11 is provided with a rib 15, see Fig. 7, which is adapted to ride upon the raised portion 14 above referred to. One end of swinging bolt 11 is notched as at 16, see Fig. 7, for detachable engagement 75 with a lug 17 formed immediately adjacent opening 6 in casing 4. The opposite end of swinging bolt 11 is forked as at 18 which forked part has horizontally journaled therein a roller 19. Positioned between a 80 lug 20 formed integral with casing 4 and the projected end 21 of swinging bolt 11 is a coiled spring 22, see Fig. 6. In order to retain the swinging bolt and spring in proper position, a plate of stamped sheet metal 23 is 85 secured to the rear of casing 4 by means of a screw 24, said screw being accommodated in the stud 12.

86 Secured to refrigerator casing 1 as by means of screws 25 is a plate 26 having 100 formed integral therewith an upper projection 27 and a lower projection 28, there being arranged between said projections 27 and 28 a recess 29 for accommodation of roller 19 of swinging bolt 11.

105 In operation the operator pulls the handle 8 outwardly thus raising that end of the swinging bolt 11 provided with roller 19, it being understood that during this movement the projection 15 of swinging bolt 11 has 110

2 moved over portion 14 of casing 4, and because of spring 22 and curve on under side of point 9, Fig. 8, and the loose connection between said swinging bolt 11 and stud 12 has tilted so that projection 16 thereof has engaged the notched part 17 of casing 4, thereby holding the swinging bolt in elevated position and the handle 8 in outwardly projecting position. Upon slamming of the refrigerator door 2 the roller 19 of swinging bolt 11 impinges against projection 27 of plate 26 on the refrigerator and point 15, Fig. 7, will tilt swinging bolt 11 thus knocking or kicking off the swinging bolt from its engagement with casing 4. A result is that the roller 19 is therefore accommodated within recessed part 29 of the keeper to efficiently lock the refrigerator door 2. In the event that the swinging bolt is in the position shown in Figs. 2 or 6, for example, this is in a relatively horizontal position, slamming of the door 2 causes roller 19 to ride over lower projection 28 and seat within recess 29 of keeper 26. The plate 23 which is secured to stud 12 has stamped therefrom an inclined projection 30 which cooperates with parts 14 and 15 in connection with spring 22 to cause tilting of said swinging bolt 11.

30 Having thus described my invention, what I claim as new and desire to secure by Letters Patent, is:

35 A latch of the character stated comprising a casing of integral structure the rear of which is open and is recessed to receive a plate, a stud projected rearwardly of said

casing, a swinging bolt arranged upon a horizontal inclination and pivoted upon said stud, one end of which is provided with a spring receiving lug, the intermediate end 40 of which is notched and the opposite end of which projects longitudinally from said casing, is bifurcated, and is provided with a roller, the axis of which substantially parallels the axis of said swinging bolt, a 45 coiled spring one end of which is fixed with respect to said lug and the opposite end of which is secured with respect to said casing, the longitudinal axis of the spring and the longitudinal axis of said lever being arranged in parallelism, a projection upon the inner part of said casing with which the notched part of said swinging bolt cooperates to temporarily hold the swinging bolt in horizontally inclined position, a vertically 50 arranged handle pivoted to said casing and provided with a rearwardly extended member for engaging an apertured part of said swinging bolt, a plate detachably secured to the said recessed rear of said casing, said plate having an inclined part with which said handle cooperates to tilt said swinging bolt, a screw for removably securing said plate to said stud, a keeper having upper and lower projections, and a central recess 55 with which the roller of said swinging bolt is adapted to cooperate during a latching operation.

In testimony whereof, I have hereunto signed my name.

THOS. O. SCHRADER.
